ELECTRICAL INCANDESCENT LAMP FOR
SERIES CONNECTION

Harry F. Waters, New York, N. Y.

Application May 5, 1937, Serial No. 140,840

1 Claim. (Cl. 176—24)

The present invention relates to electrical incandescent lamps, and, more particularly, to electrical incandescent lamps particularly adapted for series connection.

It is an object of the present invention to provide an electrical incandescent lamp particularly for the purpose of series connection which is free from the disadvantages and inconveniences of conventional series-connected lamps.

It is another object of the present invention to provide a series-connected incandescent lamp which can be connected in series with a plurality of lamps of the same type and which will not interrupt the circuit of the other lamps when its filament burns out.

It is a further object of the invention to provide a series-connected incandescent lamp which embodies a resistance element connected across its filament, said resistance element being capable of carrying sufficient current for bringing the other lamps in the circuit to at least dim incandescence.

It is also within contemplation of the present invention to provide a novel and improved incandescent lamp for series connection which is simple in construction and which may be manufactured and sold at a low price.

Other and further objects and advantages of the invention will become apparent from the following description taken in conjunction with the accompanying drawing, in which

Fig. 1 illustrates a vertical sectional view of a lamp embodying the principles of the present invention;

Fig. 2 depicts a diagrammatic view of the circuit and illustrates the way in which a plurality of the novel lamps is connected;

Fig. 3 is a view similar to Fig. 1 and shows a modified embodiment of the present invention; and

Fig. 4 illustrates a vertical sectional view of an adaptor to be used for the conversion of conventional lamps into lamps embodying the invention.

Broadly stated, according to the principles of my invention, I provide a plurality of incandescent lamps having suitable sockets and wire connections. I connect such plurality of these lamps in series that the operating voltage of the lamps multiplied by the number of lamps connected in series approximately equals the full line voltage. Across each lamp I connect a resistance of suitable value which electrically by-passes the filament of the lamp. This re-

sistance may be connected and provided in the cord, it may be arranged in the lamp within the glass vessel thereof, in the base or in the socket of the lamp, and it may be provided in a separate member or adaptor interposed between the lamp base and the socket. When a set of such lamps is connected in series and is connected to a source of current of suitable voltage, current will flow through the filaments of the lamps connected in series and through the resistance elements which are also connected in series. However, if any one of the lamps will burn out and will interrupt the main circuit of the lamps, this will not cause all of the other lamps to extinguish as this was the case with the conventional lamps connected in series, because the other lamps will be supplied with current through the by-pass resistance connected across the lamp which has burnt out. Although the other lamps will light more dimly due to the increased resistance in the circuit, they will all light with the single exception of the one which has burnt out. This permits one to locate the burnt out lamp with great facility so that the said lamp may be replaced with a new one at once.

The value of the resistance element is determined at best by experiment. The resistance should be low enough to permit sufficient current to pass to light up the other lamps at least very dimly. On the other hand, it is advantageous to provide such high resistance as is compatible with this function in view of the fact that the current passing through the auxiliary circuit formed by the resistance elements does not perform any useful work and is merely converted into heat.

The invention will now be more fully described to those skilled in the art, reference being had to the accompanying drawing.

Referring now more particularly to Fig. 1, a preferred embodiment of the invention is illustrated. A sealed glass vessel 11 is provided with a filament 12 of tungsten or carbon supported in conventional manner by lead-in wires 13 and 14. Wires 13 and 14 are lead out of the glass vessel and are connected to a conventional threaded or screw base 16, and bottom contact 15 which are insulated from each other by a dielectric 17. Across wires 13 and 14 and within the glass vessel is connected a resistance element 18. This resistance element may be in the form of a wire or coil of suitable resistance. It is also possible to provide the resistance element in the form of a second or auxiliary fila-

ment connected across the main filament or filament proper. This has the advantage that the current passed through the auxiliary filament is not wasted but is converted into radiant energy. In Fig. 2, a plurality of such lamps is shown connected in series. Each of lamps 21 is provided with a filament 22 and with a resistance element 28 within the glass vessel thereof.

10 From the preceding description, the operation of the improved series lamp will be readily understood by those skilled in the art. When the group of lamps connected in series is connected to a source of current of suitable voltage, current 15 will pass through all of the filaments and through all of the resistance elements. As soon, however, as one of the filaments burns out, current will flow only through the corresponding resistance element which will permit the other lamps to 20 light at least dimly and to readily reveal the faulty lamp.

The modified embodiment of the invention shown in Fig. 3 has a structure similar to that of Fig. 1 and comprises a sealed glass vessel 31, a filament 32, supporting wires 33 and 34 which are connected to bottom contact 35 and base 36, respectively, insulated by dielectric 37. Resistance element 38 is located in the base of the lamp and is connected between screw base 36 and bottom contact 35. In view of the similarity of construction, the operation of this modified embodiment will be readily understood by those skilled in the art without any further explanation.

Fig. 4 depicts an adaptor adapted to be interposed between a conventional lamp and a conventional socket. The adaptor comprises an insulative body portion 41, a threaded female portion 42 adapted to hold a lamp base, and a threaded male portion 43 integrally formed therewith and adapted to be inserted into a conventional socket. Bottom contacts 44 and 45 are

5 inserted and held by insulative rings 47 and 49 in the female and the male portions, respectively, and are connected electrically by a conductor 48. In the male portion of the adaptor is located a resistance element 48 which is connected between members 43 and 45. When a conventional lamp is inserted into the threaded female portion 42, resistance element 48 will be connected across the lamp and will function in the same way as in the embodiments shown in Figs. 1 to 3.

10 Although the present invention has been described in connection with a few selected embodiments thereof, variations and modifications may be resorted to by those skilled in the art without departing from the spirit and scope of the present invention. I consider all of these variations and 15 modifications as within the true spirit and scope of the present invention as disclosed by the present description and defined by the appended claim.

20 I claim:

An incandescent lamp for series connection comprising a sealed glass vessel, a filament in said vessel, lead-in wires extending into said vessel and forming a gas-tight seal therewith for supporting said filament, a base cemented to said vessel and having contacts therein electrically connected to said wires for passing current through said filament, and a resistance element 25 located within said base and permanently connected across said wires and across said filament, said resistance element being so proportioned as to pass substantial current during the normal operation of said filament, and in case of rupture 30 of said filament being capable of passing sufficient current to the filaments of other lamps of the same type connected in series therewith to bring such filaments to at least dim incandescence.
